UNITED STATES PATENT OFFICE

109,040

DESIGN FOR A RADIO CABINET

Irwin Feitler, Chicago, Ill.

Application November 8, 1937, Serial No. 72,700

Term of patent 3½ years

To all whom it may concern:

Be it known that I, Irwin Feitler, a citizen of the United States, residing at Chicago, in the county of Cook and State of Illinois, have invented a new, original, and ornamental Design for a Radio Cabinet, of which the following is a specification; reference being had to the accompanying drawing, forming a part thereof.

In the drawing:

Fig. 1 is a front perspective view of a radio cabinet showing the body portion in the vertical position;

Fig. 2 is a front perspective view of the same but with the body portion in an inclined position; and,

Fig. 3 is a side perspective view showing the body portion in a horizontal position.

I claim:

The ornamental design for a radio cabinet, substantially as shown.

IRWIN FEITLER.
